DEVELOPING APPARATUS

Lewis D. Andrews, St. Marys, Pa., assignor to
 Stackpole Carbon Company, St. Marys, Pa., a
 corporation of Pennsylvania

Application October 27, 1938, Serial No. 337,193

10 Claims. (Cl. 95—90.5)

This invention relates to apparatus for developing strips of photographic film, and more particularly to a daylight loading developer for "candid" camera film and the like.

5 It is among the objects of this invention to provide developing apparatus which is simple and inexpensive in construction, which can be easily loaded and operated in daylight, and which is formed from a very few parts.

10 In accordance with this invention a receptacle or tank has a developing chamber or area and a film cartridge receiving area connected by an intermediate area in which means is disposed for guiding an undeveloped exposed film from the cartridge to the developing area. Rotatably mounted in the developing area of the tank is a reel provided with spiral grooves in the inner faces of its flanges for receiving the opposite edges of the film. The reel is made in two parts 15 separable at the hub, the two parts of the hub being adapted to grip the leading end of the film between them. The upper flange of the reel serves as a cover for the developing area of the tank. The rest of the tank is normally closed by another cover, except for an opening which 20 is left over the cartridge-receiving area for receiving a cylindrical member. This member, which extends down into the tank, is adapted to rotatably receive the film cartridge, and is provided with a slot in its side wall through which 25 the film passes to the guiding means. The top of the cylindrical member is normally closed by a rotatable knob which is adapted to be detachably connected to the top of the cartridge. After 30 the undeveloped film has been wound onto the reel by turning the reel, the trailing end of the film is torn from the cartridge by turning the reel and cartridge in opposite directions. The cartridge-receiving member is then turned so that 35 its slot can not admit light to the developing chamber, whereupon the empty cartridge is removed. The developing liquid is then poured into the tank through the empty cylindrical member.

The preferred embodiment of the invention is 40 illustrated in the accompanying drawings in which Fig. 1 is a plan view of my developer; Fig. 2 is a transverse section thereof taken on the line II—II of Fig. 1; Fig. 3 is a plan view of the tank with the intermediate cover and upper flange 45 of the spool removed and with the film cartridge and its housing shown in section; and Fig. 4 is a longitudinal section of the developer taken on the line IV—IV of Fig. 1.

Referring to Figs. 3 and 4 of the drawings, 50 part of the side wall of the tank forms a wall for

the major portion of a circular area 1 in which exposed film is developed, as will be described presently. The side wall of the tank at its opposite end forms all but about ninety degrees of the wall of a smaller circular area 2 adapted 5 to receive a cartridge 3 containing a roll of undeveloped film 4. The top of the tank's intermediate area 5, which connects the open sides of the developing and cartridge areas, is normally closed by a removable cover 6 that rests in 10 recesses 7 and 8 formed in the top of the tank's side wall. The inner edge of this cover is arcuate and, together with the arcuate side wall of the developing chamber, forms a complete circle provided with upstanding ribs 9 and 11. As shown 15 in Fig. 4, the bottom of the tank at the center of the developing area is provided with circular boss 12 which projects up into a circular opening 13 in the bottom of a film-developing reel 14 removably disposed in the tank. This boss not only 20 positions the reel in the tank, but also serves as a bearing that prevents the lower flange 16 of the reel from touching the bottom of the tank. In accordance with this invention, the upper flange 25 17 of the reel forms a cover for the developing area of the tank. That is, the upper flange extends outwardly across ribs 9 and 11, and is provided near its edge with a circular recess 18 for receiving them to prevent light from entering the tank between the ribs and reel.

The inner face of each flange of the reel is 30 provided with a spiral groove 21 for receiving the edge portions of a film in a well-known manner. According to this invention, the reel is divided into two parts which are detachably connected together at its hub. For this purpose the center of each flange is provided with an inwardly extending boss, the lower one 22 being hollow for telescopically receiving the upper one 23. To assure the ends of the spiral grooves being 35 opposite each other when the reel is assembled, the upper boss is provided with an integral longitudinal key 24 that slides down into a slot 26 in the wall of the hollow boss. The wall of the hollow boss is provided with a longitudinal slot 40 27 for receiving the leading end of the film, the tip of the film being bent over and wedged between the two bosses when they are telescoped. Preferably, there are about three of these slots so that 45 the solid boss can be wedged in the hollow boss without danger of breaking it.

Another feature of this invention is that in the cartridge-receiving area 2 of the tank a hollow cylindrical housing 31 is suspended by a peripheral flange 32 at its upper end which rests on 50 55

cover 6 and the side wall of the tank. This housing is adapted to rotatably receive a film cartridge and is provided with a vertical slot 33 open at its lower end and through which the film 5 is drawn from the usual slot in the side of the cartridge. The hub 34 at the bottom of the cartridge is rotatably mounted in a circular recess 35 in the bottom of the tank. The upper portion of the cartridge housing engages the side 10 wall of the tank, but its lower portion is decreased in diameter to provide a space for receiving an extension 36 of a metal guide member 37. This guide member is of the customary shape for bowing the film transversely to decrease its width 15 so that it can enter the reel between its flanges. The extension of the guide member is bent around the cylindrical housing which holds it in position. Although extension 36 and the housing can be rotated relative to each other, the film itself prevents the extension from sliding down on the 20 housing.

During the winding of the film from the cartridge to the reel, the top of housing 31 is closed by a knob 38 in order to prevent light from entering 25 the housing. This knob is held in position by a flange 39 extending upwardly from the outer edge of the housing's peripheral flange 32, and has a depending split boss 41 (Fig. 4) for projecting into the hollow upper end of the film 30 cartridge and frictionally gripping it.

To load this developer, the leading end of the film is pulled from the film cartridge and then housing 31 is slipped down over the cartridge with the end of the film extending through slot 33. Knob 38 may then be placed on top of the housing with its split boss 41 projecting into the cartridge. The film is threaded through guide 37 after which these members are placed in operative 35 position in the tank followed by cover 6. The leading end of the film is passed through one of the slots 27 in the hollow boss 22 of lower reel flange 16, the only part of the reel that is in the tank at this time, and is clamped in place by inserting the solid boss 23 of upper reel flange 17 in the lower boss. This likewise assembles 40 the reel and closes the top of the developing chamber. The entire tank is now closed and light-proof and the film can be wound onto the reel by turning it by the knob 42 on top of it. After the exposed film has been transferred from 45 the film cartridge to the reel in this manner, knobs 38 and 42 are turned in opposite directions to apply tension to the film and cause its weakened trailing end to tear from the cartridge spool. Housing 31 is then turned by a lateral lug 43 at its upper end (Fig. 1) to bring its slot 33 adjacent the side wall of the tank so that light can 50 not enter the developing area of the tank when the film cartridge is removed from the housing by lifting knob 38. Developing liquid is supplied to the tank by pouring it in through empty housing 31 which is spaced from the bottom of the tank. The film can be agitated while immersed 55 in the developing fluid by merely turning reel 14 by means of knob 42.

According to the provisions of the patent statutes, I have explained the principle and construction of my invention and have illustrated and described what I now consider to represent its best embodiments. However, I desire to have 60 it understood that, within the scope of the appended claims, the invention may be practiced otherwise than as specifically illustrated and described.

I claim:

75 1. A daylight-loading film developer compris-

ing a tank having a bottom wall and an upright side wall, a removable film-receiving reel rotatably mounted within one end of the tank and having an upper flange forming a cover for the underlying area of the tank, means spaced laterally from said reel and mounted within the opposite end of the tank for rotatably supporting a film cartridge therein, a separate removable cover for the cartridge-receiving area of the tank, a guide member disposed in the intermediate area 10 of the tank between said means and reel for guiding film from the cartridge to the reel, and a cover for said intermediate area.

2. A daylight-loading film developer comprising a tank having a bottom wall and an upright side wall, a removable film-receiving reel rotatably mounted within one end of the tank and having an upper flange forming a cover for the underlying area of the tank, a cartridge-receiving member spaced laterally from said reel and rotatably mounted within the opposite end of the tank, said member being provided in its side wall with a film-receiving slot, a rotatable cover mounted on said member and adapted to be detachably connected to the upper end of a film cartridge disposed therein, a guide member disposed in the intermediate area of the tank between said cartridge-receiving member and reel for guiding film from the cartridge to the reel, and a stationary removable cover for said intermediate area.

3. A daylight-loading film developer comprising a tank having a bottom wall and an upright side wall, a removable film-receiving reel rotatably mounted within one end of the tank and having an upper flange forming a cover for the underlying area of the tank, a cylindrical cartridge-receiving member spaced laterally from said reel and rotatably disposed within the opposite end of the tank, a film-guiding member disposed in the intermediate area of the tank between said cylindrical member and reel, a stationary removable cover for said intermediate area, the upper end of said cylindrical member being provided with a flange resting on said stationary cover and the side wall of the tank for supporting the member, the side wall of said cylindrical member being provided with a film-receiving slot, and a separate removable cover for said cylindrical member.

4. A daylight-loading film developer comprising a tank having a bottom wall and an upright side wall, a removable film-receiving reel rotatably mounted within one end of the tank and having an upper flange forming a cover for the underlying area of the tank, a cartridge-receiving member spaced laterally from said reel and rotatably mounted within the opposite end of the tank, said member being provided in its side wall with a film-receiving slot, a rotatable cover mounted on said member and adapted to be detachably connected to the upper end of a film cartridge in said member, a guide member supported at one end by said cartridge-receiving member and projecting into the intermediate 65 area between the cartridge-receiving member and the reel, and a stationary removable cover for said intermediate area.

5. A daylight-loading film developer comprising a tank having a bottom wall and an upright side wall, a removable film-receiving reel rotatably mounted within one end of the tank and having an upper flange forming a cover for the underlying area of the tank, a cylindrical cartridge-receiving member spaced laterally from said 75

reel and rotatably disposed within the opposite end of the tank, the side wall of said member being provided with a film-receiving slot, a film-guiding member disposed in the intermediate area of the tank between said cylindrical member and reel, a stationary removable cover for said intermediate area, the upper portion of the side wall of said cylindrical member being substantially in engagement with said stationary cover and side wall of the tank, the lower portion of the side wall of said cylindrical member being of reduced thickness to provide a space between it and the side wall of the tank, said film guide having an extension encircling said cylindrical member in said space, and a cover for the cylindrical member.

6. A daylight-loading film developer comprising a tank having a bottom wall and an upright side wall, a removable film-receiving reel rotatably mounted within one end of the tank and having an upper flange forming a cover for the underlying area of the tank, a cartridge-receiving member spaced laterally from said reel and rotatably mounted within the opposite end of the tank, the side wall of said member being provided with a film-receiving slot, a rotatable cover mounted on said member and adapted to be detachably connected to the upper end of a film cartridge in the member, the bottom of the tank being provided with a recess for receiving the hub of the film cartridge, a guide member disposed in the area of the tank between said cartridge-receiving member and reel for guiding film from the cartridge to the reel, and a cover for said intermediate area.

7. A daylight-loading film developer comprising a tank having a bottom wall and an upright side wall, a removable film-receiving reel rotatably mounted within one end of the tank and having an upper flange forming a cover for the underlying area of the tank, a cylindrical cartridge-receiving member spaced from said reel and rotatably disposed within the opposite end of the tank, a film-guiding member disposed in the intermediate area in the tank between said cylindrical member and reel, a stationary removable cover for said intermediate area, the upper end of said cylindrical member having a peripheral flange resting on said stationary cover and the side wall of the tank for supporting it, the outer edge of said flange being provided with an upstanding flange, and a knob rotatably mounted on said peripheral flange and provided with a central depending portion adapted to project into the upper end of a film cartridge in said cylindrical member and to frictionally grip the cartridge.

8. A daylight-loading film developer comprising a tank having a bottom wall and an upright side wall, a removable film-receiving reel rotatably mounted within one end of the tank and having an upper flange forming a cover for the underlying area of the tank, means spaced laterally from said reel for rotatably supporting a film cartridge within the opposite end of the tank,

a separate removable cover for the cartridge-receiving area of the tank, a guide member disposed in the intermediate area of the tank between said means and reel for guiding film from the cartridge to the reel, and a cover for said intermediate area, the inner face of each flange of the reel being provided with a spiral film-receiving groove, said reel being formed in two parts with an axial boss projecting inwardly from each flange, and one of said bosses being hollow for telescopically receiving the other boss and being provided with a longitudinal slot for receiving the leading end of a film, said bosses being adapted to wedge said leading end between them.

9. A daylight-loading film developer comprising a tank having a bottom wall and an upright side wall, a removable film-receiving reel rotatably mounted within one end of the tank and having an upper flange forming a cover for the underlying area of the tank, means spaced laterally from said reel for rotatably supporting a film cartridge within the opposite end of the tank, a separate removable cover for the cartridge-receiving area of the tank, a guide member disposed in the intermediate area of the tank between said means and reel for guiding film from the cartridge to the reel, and a cover for said intermediate area, the inner face of each flange of the reel being provided with a spiral film-receiving groove, said reel being formed in two parts with an axial boss projecting inwardly from each flange, and one of said bosses being hollow for telescopically receiving the other boss and being provided with a longitudinal slot for receiving the leading end of a film, said bosses being adapted to wedge said leading end between them, and said bosses being provided with a registering key and slot to assure correct positioning of the two spiral grooves relative to each other.

10. A daylight-loading film developer comprising a tank having a bottom wall and an upright side wall, a removable film-receiving reel rotatably mounted within one end of the tank and having an upper flange forming a cover for the underlying area of the tank, means spaced laterally from said reel for rotatably supporting a film cartridge within the opposite end of the tank, a separate removable cover for the cartridge-receiving area of the tank, a guide member disposed in the intermediate area of the tank between said means and reel for guiding film from the cartridge to the reel, and a cover for said intermediate area, the inner face of each flange of the reel being provided with a spiral film-receiving groove, said reel being formed in two parts with an axial boss projecting inwardly from each flange, and one of said bosses being hollow for telescopically receiving the other boss and being provided with a plurality of laterally spaced longitudinal slots extending inwardly from the free end of the boss, at least one of said slots being adapted to receive the leading end of a film, said bosses being adapted to wedge said leading end between them.

LEWIS D. ANDREWS.
